UNITED STATES PATENT OFFICE.

GEORGE A. BRIGGS, OF ELKHART, INDIANA.

ALTERNATING-CURRENT MAGNETO FOR IGNITION AND COMBUSTION ENGINES.

1,100,651.

Specification of Letters Patent. Patented June 16, 1914.

Application filed January 22, 1912. Serial No. 572,566.

To all whom it may concern:

Be it known that I, GEORGE A. BRIGGS, a citizen of the United States, residing at Elkhart, in the county of Elkhart and State 5 of Indiana, have invented certain new and useful Improvements in Alternating-Cur- 10 rent Magneto's for Ignition and Combustion Engines, of which the following is a specification.

10 My invention relates to an improvement in alternating current magneto's for ignition and combustion engines, and what is known as the dual system, the current being generated in the magneto and stepped up in a 15 transformer coil, the circuit being connected in with a double throw switch whereby the motor can be operated on either magneto current or battery current.

15 The invention consists in certain novel 20 features of construction and combination of parts which will be hereinafter described and pointed out in the claims.

In the accompanying drawings, Figure 1 25 is a vertical sectional view; Fig. 2 is an end view of the circuit end of the magneto having the circuit breaker cover and distributor cover removed; Fig. 3 is a view in side elevation; and Fig. 4 is an end elevation.

20 A represents the casing, and 1 is the base. 25 A shuttle armature 2 is journaled in the casing. A head 3 is connected at one end, to which head a drive shaft 4 is connected which passes through an end plate 5. Ball 30 races 6 and 7 are formed in the end plate, 35 in which balls 8 are received for forming a journal for the shaft. A head plate 9 is connected to the other terminal of the armature 2, and connected to the head plate 40 is an armature shaft 10. An end plate 11 45 is provided with ball races 12 and 13, between which balls 14 are received for forming 45 a journal for the armature shaft 10. A gear wheel 15 is mounted on the armature shaft which meshes with a larger gear wheel 16 on the distributor shaft 17. The distributor shaft 17 is journaled in a hub 18 50 formed in the end plate 11, ball races 19 and 20 being formed in the hub, in which balls 21 are received for forming journals for 55 the shaft 17. An insulated hub 22 is connected to the gear wheel 16, and mounted on the insulated hub is a metal fan or distributor plate 23. An insulated block 24 is mounted on the end plate 11 and is held there- 55 on by means of studs 25 (Fig. 4). An insu-

lated cover 26 is provided for closing the chamber 27 formed in the block 24 in which the distributor plate 23 travels. The cover is provided with a recess in which a bushing 28 is received, and mounted in the bushing 60 is a carbon brush 29. A spring 30 is received between the closed end of the bushing 28 and the brush for causing the brush to be retained in contact with the distributor plate 23.

65 The terminals a , b , c , d and e (Figs. 1 and 2) are all connected to the insulated block 24. The terminals a , b , d and e have wires 31 leading therefrom through the insulated block 24 to contact points 32 which are in 70 the path of the distributor plate 23. These four terminals are electrically connected to a high tension wire to the spark plugs and from cylinders of the combustion engine (not shown). The terminal c is connected 75 with a high tension wire to what is known as a high tension terminal of a transformer coil (not shown), and leading from this terminal c is a wire 33 which makes contact with a spring 34. A wire 35 is connected 80 to the spring 34 and to the bushing 28, whereby an electric current passes from the terminal c to the distributor plate 23 through the carbon brush 29.

85 A rod 36 is mounted in and insulated from the armature shaft and connected to the rod is a nut or collar 37. A circuit breaker cover 40 is mounted on the casting 41 which forms the body of the circuit breaker, which body has a working fit on 90 the hub 42 formed on the end plate 11. The cover is fastened to the body by means of studs 43, 43, which are provided with thumb nuts 44. Binding posts or terminals 38, 39, are connected to the cover 40. The 95 terminal 38 carries a spring 45 which engages a contact post 46 which is mounted on the body 41 of the circuit breaker. The terminal 39 has a spring 47 connected thereto which is provided with a cup 48 in which 100 a carbon 49 is inserted, the carbon being held in contact with the nut or collar 37 on the rod 36. A metal tube 50 is connected to the end plate 11, and a thumb nut 51 is connected thereto which clamps a spring 52 105 to the tube, causing the spring to be brought against the circuit breaker cover 40 for taking up any lost motion of the wear in the oscillation of the circuit breaker.

110 The body of the circuit breaker 41 is pro-

vided with a curved slot 53 through which a screw 54 passes, which screw is connected to the hub 42 of the end plate 11 for locking the circuit breaker in any of its adjusted 5 positions, the screw permitting of the circuit breaker body being oscillated to suit the conditions for regulating the timing of the spark with the motor and the length of the slot gages the number of degrees to which 10 the circuit breaker can be locked.

Mounted upon the armature shaft 10 is a two-faced cam 55. A circuit breaker hammer or lever 56 is pivotally mounted on the body of the circuit breaker 41 and is provided 15 with a roller 57 which is normally held in engagement with the cam 55 by a spring 58. A contact spring 59 is provided with a platinum point 60. The platinum point makes contact with a platinum point 61 on 20 contact screw 62. The contact screw 62 is held in the contact post 46 by a lock nut 63. The compression spring 58 and contact spring 59 are connected to the body 41 of the circuit breaker by a binding post 64. Permanent 25 steel horse-shoe magnets 65, 66, are mounted in the casing A, and their lower ends form the fields at each side of the armature 2.

An oil cup 67 is formed in the end plate 5 and leading therefrom is a conduit 68 for 30 conducting the oil to the journal bearings 6 and 7 of the drive shaft 4. A tube 69 conducts the oil from the oil cup 67 to the journal bearings of the distributor shaft 17 and a tube 70 conducts the oil from said 35 cup to the journal bearings of the armature shaft 10.

The shuttle armature 2 carries a coil of magnet wire 71, one end of which is electrically connected to the body of the core 40 at 72 and the other terminal is connected at 73 to the rod 36 of the armature shaft 10. It will be seen that when the armature 2 is revolved within its fields, electrical current is set up or set in motion in the coil of wire 45 71, one spark of the plug going to the ground at 72 and the opposite spark of the plug going to the terminal 73, and then through the conductor rod 36 to the carbon brush 49, and thence conducted to terminal 50 39, shown in Fig. 4. The rotation of the armature 2 transmits a rotary movement to the armature shaft 10, thereby transmitting a rotary movement to the gear wheel 16 through the gear 15. The rotation of the 55 gear 16 causes the distributor plate 23 to be rotated, causing it to make contact with the contact points 32. It is to be remembered that the high tension current from the transformer flows to the terminal c, and from the 60 terminal the current is conducted through the wire 33 to the spring 34, thence to the wire 35, and thence to the brush 29 which is in engagement with the distributor plate 23, so that when the plate 23 makes contact

with one of the contact points of one of the 65 terminals, the current will be carried out through the wire leading to the terminal at the upper end of the distributor and to the cylinder of the engine, as is timed in respective relation. The rotation of the armature shaft 10 causes the cam 55 to be revolved. The cam works against the roller 70 57 of the lever 64, causing the upper end of the hammer or lever to be oscillated for causing the hammer to actuate the contact 75 spring 59 for breaking the primary circuit between the contacts 60 and 61.

The low tension alternating current system stepped up to a high tension is so common of to-day and so well understood that it is 80 deemed unnecessary to show a wiring diagram, as it would be seen that the ground of the magneto will be only permanent on the low tension current. The terminal 39, which is electrically connected to the circuit 85 end of the armature, will be the opposite end of the circuit. The contact post 46 being insulated from the metal parts of the circuit breaker body and electrically connected to the terminal 38, makes the third terminal 90 for connecting with a transformer coil (not shown) which is commonly used in this type of magneto. The armature being of a shuttle type has two cycles with each revolution. The cam having two projections will operate 95 the circuit breaker twice at each revolution of the armature. The relation of the gears between the armature shaft and the distributor shaft being two to one, will operate the distributor shaft one half the speed 100 of the armature shaft, or, in other words, the armature shaft makes two revolutions to one revolution of the distributor fan, and every time the armature has made one half a revolution or one cycle, the distributor fan 105 or plate has passed from one terminal to the next in rotation.

Having fully described my invention, what I claim as new and desire to secure by Letters Patent, is:—

110

1. In a magneto, the combination with an armature and an armature shaft, of a circuit breaker consisting of a stationary contact member and a movable contact member, a cam mounted on the armature shaft adapted to be rotated upon the rotation of the armature shaft, a hammer pivotally mounted in the circuit breaker, means for holding the hammer in engagement with the cam, said cam adapted to actuate the hammer for causing the hammer to come in contact with the movable contact member for breaking the circuit.

115

2. In a magneto, the combination with an armature and an armature shaft, of a circuit breaker journaled around the axis of the armature shaft, means for oscillating the circuit breaker around the axis of the arma-

120

125

ture shaft, an insulated bracket mounted in the circuit breaker, a stationary contact member adjustably mounted on the bracket, a movable contact member mounted in the 5 circuit breaker and normally in engagement with the stationary contact member, a hammer, and a cam mounted on the armature shaft adapted to actuate the hammer for causing the hammer to come in contact with.

the movable contact member for breaking 10 the circuit.

In testimony whereof I affix my signature, in the presence of two witnesses.

GEORGE A. BRIGGS.
